BRACKET FOR A BED SPRING OR THE LIKE

Ray C. Brewer, 56 E. Acacia St., Salinas, Calif.

Filed Nov. 28, 1960, Ser. No. 62,997

Term of patent 14 years

(Cl. D5—2)

The essential features of my design reside in the elongated rectangular back member in combination with the thickened base portion and recessed bottom, all as shown.

I claim:

The ornamental design for a bracket for a bed spring or the like, substantially as shown and described.
